PHILADELPHIA, PENNSYLVANIA, A CORPORATION OF PENNSYLVANIA.

DRYING-MACHINE.

1,374,709.

Specification of Letters Patent. Patented Apr. 12, 1921.

Application filed December 18, 1919. Serial No. 345,820.

To all whom it may concern:

Be it known that we, THOMAS ALLSOP and WALTER W. SIBSON, citizens of the United States, residing in Philadelphia, in the county of Philadelphia and State of Pennsylvania, have invented certain new and useful Improvements in Drying-Machines, whereof the following is a specification, reference being had to the accompanying drawings.

The invention relates to drying machines, and more specifically to that class of such machines particularly adapted for drying china, crockery, etc.

Ordinarily, machines of this type, comprise an inclosure through which the articles to be dried are carried by a slowly moving conveyer, and subjected at the same time, to heated air circulated within the inclosure by appropriate propelling means. For various reasons incidental to the operation of such machines, it is often necessary to temporarily arrest the conveyer, with the result that the various portions of the same come to rest in close proximity to the heating devices in the drier. As a consequence, the articles supported by these portions of the conveyer would be apt to become warped or fractured if subject, for any appreciable time, to the direct action of the heat, and it is therefore highly advantageous to maintain the circulation of the air during such suspension periods. In order to meet these essential requirements, we propose to employ a driving system for the various moving parts of the drying machine, which comprises means whereby the activity of the conveyer may be independently controlled without affecting the constant operation of the air propelling means.

The invention also comprehends mechanism whereby the direction of rotation of the air propelling means is automatically reversed periodically, so that uniform drying of the articles under treatment is greatly facilitated.

A further object of the invention is to divert a portion of the conveyer run to the exterior at the loading end of the drier in such manner as to overhang a dipping vat for the glazing solution located at this point. By this arrangement, the articles dipped by the operative and placed upon the conveyer, are given an opportunity to drain prepara-

tory to entering the inclosure, and the excess solution permitted to drip back into the vat.

A structure conveniently embodying all these various features of our invention is described hereinafter, while the scope and essentials of the invention are indicated in our claims.

In the drawings, Figure I, is a longitudinal sectional view through a drying machine conveniently embodying our invention.

Fig. II, is an elevation of the right hand, or delivery end of the machine.

Fig. III, is a partial plan view of the structure showing more particularly the driving system;

Fig. IV, is an end elevation of the organization shown in Fig. III.

The drying machine herein illustrated is of a typical form and comprises an inclosure 1, which is traversed by a sprocket chain conveyer diagrammatically represented at 2, in dot and dash lines. The latter moves over a circuitous course under the guidance of a series of sprockets 3. The inclosure is internally divided by a transversely extending, partitioning unit 4, having a U-shaped, cross sectional configuration, into an inner drying chamber 5, and channels 6, 7 and 8, through which portions of the conveyer run extend for reasons which will become apparent later. The inner or drying chamber 5, is in turn spanned by a transverse partitioning unit 9, which has the same configuration as the one previously described, but is inverted with respect thereto. By this arrangement, the drying chamber is subdivided into a main or central compartment 10, and auxiliary passages 11, 12 and 13. Within the horizontal component 15, of the partitioning unit 9, is a rotary fan 16, under the action of which the air is propelled in divided circuits, in the directions shown by the arrows in Fig. I, through the drying chamber, and over courses completed by the several auxiliary subdivisions. In order to facilitate such circulation, the structure is provided above the fan with a transverse ridge comprising deflecting surfaces 17 and 18. Distributed at various points within the drying chamber are banks of heating coils 19, which are functional in modifying the atmosphere in the chamber in a well known manner.

The machine is operated by a driving sys-

tem which comprises an overhead power shaft 20, common to both the conveyer and the circulating fan. In order to drive the former, we have provided a counter shaft 21, which is actuated from shaft 20, by a belt connection 22. The motion of shaft 21 is transmitted through a worm gear couple 23, to a vertical shaft 25, which in turn drives, by means of another interposed worm gear couple 26, the shaft 27, of the conveyer system at the upper right hand corner of the structure in Fig. I. In order that the drive of the conveyer may be independently controlled, the pulley on shaft 21 included 10 in its driving connection 22 is connected to said shaft through a clutch 30, which is shiftable by means of a handle 31, extending to a point conveniently accessible to the operative.

20 Coming back once more to the circulating fan 16, it will be noted that the latter is mounted upon a vertical shaft 35, journaled in suitable bearings 36, and driven by means of bevel gears 37, from a horizontal shaft 38, the latter being provided at its outer end, as shown in Fig. IV, with two tight pulleys 39, 40, and an intermediate loose pulley 41. Through the coöperation of open and crossed belts 42 and 43, capable of being 25 simultaneously shifted, the shaft 38, may be driven either in one direction or the other. For example, when these belts occupy the position shown in Fig. IV, it will be seen that the open belt 42, is effective in 30 driving the pulley 39, while the belt 43, simply runs idle upon the intermediate pulley 41. When the belts are simultaneously shifted to the right, such transposition causes the crossed belt 43, to become 35 active upon the pulley 40, and drive the shaft in the opposite direction. In order 40 that such reversal of the drive of the shaft 38, may be periodically effected, we have provided a controlling mechanism comprehensively indicated at 44. This controlling mechanism is operated from the shaft 38, and the latter is accordingly provided with 45 a worm 45, which drives a worm wheel 46, mounted upon a shaft 47, suspended from 50 overhead by appropriate bearing hangers 48. Projecting laterally from the side of the worm gear 46, are pins or lugs 49, 50, which are adapted to operate alternately from opposite sides upon a lever 51, fulcrumed at 55 52, to the top of the drying machine and carrying at its upper end an adjustable weight 53. When the worm gear 46, is rotated in one direction, the projection 49, engaging the lever 51, from one side carries 60 the same toward the right in Fig. IV. After reaching a position slightly beyond the vertical, the lever drops automatically to the right of its fulcrum 52. When the worm gear moves in the opposite direction, the 65 projection 50, becomes effective to shift the

lever 51, to the left, with the result that the latter ultimately drops to the corresponding side of its fulcrum. These oscillations of said lever are effective upon a shifter rod 54, connected thereto at 55, and guided at 70 its opposite end in a suspension slide bearing 56. This shifting rod 54, carries a number of prong members 57, between which the belts 42 and 43 run, and also a pair of collars 58 and 59, which properly 75 limit the extent of its longitudinal shifting.

Referring again to Figs. I and II, it will be noted that the end walls 60 and 61, of the inclosure are respectively provided with openings 62, 63. The opening 62, is somewhat larger than the one at the opposite end of the structure so as to permit the diversion of a portion of the conveyer run to the exterior. This extension of the conveyer run overhangs a vat 65. Previous to mounting 80 the articles to be dried upon the conveyer, the operative dips them into the vat 65, containing a glazing solution. The charges to be dried may be mounted on the conveyer in any approved manner, but in typical apparatus for drying earthenware, such a conveyer usually comprises a series of pivotally suspended carriers 66. By the peculiar disposal of the diverted portion of the conveyer run, the articles placed upon the conveyer 90 carriers are given an opportunity to drain before entering into the inclosure, and, further, the excess solution is permitted to drip back into the dipping vat 65. This not only entails economy in so far as the glazing 100 solution is concerned, but, what is of more importance, prevents such excess solution from dripping from the articles upon one carrier to those upon another during progression through the apparatus.

105 The operation of the device is as follows:

As previously stated, the articles to be dried are first dipped into the vat 65, and thence placed upon the conveyer carriers 66, and under the slow movement of the 110 conveyer gradually progressed through the inclosure 1. During such progression the conveyer charges are subjected to the drying influence of the circulated air heated by the coils 19, and propelled alternately, 115 first in one direction as indicated by the arrows, and then conversely, over divided circuits established by the peculiar division of the drying chamber. The reversals of rotation of the fan 16, are effected by the 120 simultaneous shifting of the belts 42 and 43, under the control of the mechanism 44. Thus when the shaft 38, is driven in one direction, the worm gear 46, will be rotated in a corresponding direction, while, when 125 the belts are shifted, said shaft 38, being reversed, will cause the wheel 46, to follow suit. The duration of these alternate periods is determined by the relative positions of the pins 49 and 50 and their effect upon 130

the weighted lever 51, as already understood. By this arrangement, it will be seen that the air within the inclosure is periodically propelled first in one direction 5 and then in another thereby accordingly effecting variations in the direction of impingement against the articles supported upon the conveyer. When it becomes necessary, for any reason whatever, to suspend 10 the operation of the conveyer, this may be accomplished by simply shifting the lever 31, to disengage the clutch 30. It will be remembered that the design of the driving system of the machine is such that the operation 15 of the conveyer may be suspended without interfering in any way with the operation of the circulating fan 16, so that the articles supported by the portions of the run of the conveyer which come to rest 20 in close proximity to the heating coils 19, are not directly influenced by reason of such proximity, being protected against any detrimental results by the continued circulation of the air. After the completion of 25 the drying operation, the articles are withdrawn from the conveyer carriers through the opening 63, in the wall 61, of the inclosure.

Having thus described our invention, we 30 claim:

1. In a drying machine, the combination of an inclosure; a rotary fan for circulating the air within the inclosure; a conveyer traversing the inclosure; a common driving 35 system for said conveyer and said fan, including means whereby the movement of the conveyer may be suspended without interfering with the operation of said fan; a reversible driving mechanism for said fan 40 comprising an actuating shaft; driving connections whereby said shaft may be rotated in either direction; and shifting devices subject to the control of said shaft for connecting the latter alternately to said driving 45 connections.

2. In a drying machine, the combination of an inclosure; a rotary fan for circulating the air within the inclosure, a conveyer traversing the inclosure; a common driving 50 system for said conveyer and said fan, including means whereby the movement of the conveyer may be suspended without

interfering with the operation of said fan; a reversible driving mechanism for said fan comprising an actuating shaft; driving connections whereby said shaft may be rotated in either direction; a rotative member actuated by said shaft; a lever so weighted as to be capable of falling automatically from the vertical to either side of its fulcrum 60 under the control of the rotative member; and interposed means for connecting said shaft alternately to said driving connections under the action of said lever.

3. In a drying machine, the combination 65 of an inclosure; a rotary fan for circulating the air within the inclosure; a reversible driving mechanism for said fan comprising a shaft having two tight pulleys and an intermediate loose pulley; an open belt and a 70 crossed belt simultaneously shiftable in proper relation to said pulleys to cause the shaft to be rotated alternately in opposite directions; and means controlled by said shaft to cause said belts to be shifted at 75 regular intervals.

4. In a drying machine, the combination 80 of an inclosure; a rotary fan for circulating the air within the inclosure; a reversible driving mechanism for said fan comprising 85 an actuating shaft having two tight pulleys and an intermediate loose pulley; an open belt and a crossed belt simultaneously shiftable in proper relation to said pulleys to cause the shaft to be rotated alternately in 90 opposite directions; a worm gear driven by said shaft; a lever so weighted as to be capable of falling automatically from the vertical to a position at either side of its fulcrum; projections carried by said gear and 95 adapted to be alternatively operative from opposite sides in moving said lever slightly beyond the vertical; and a belt shifter connected to said lever and functional in simultaneously shifting said belts.

In testimony whereof, we have hereunto signed our names at Philadelphia, Pennsylvania, this twelfth day of December, 1919.

THOMAS ALLSOP,
WALTER W. SIBSON.
